UNITED STATES PATENT OFFICE.

ROBERT C. SCHEMML, OF UNION CITY, INDIANA.

DEVICE FOR TURNING BACKSTAYS.

SPECIFICATION forming part of Letters Patent No. 655,582, dated August 7, 1900.

Application filed January 25, 1900. Serial No. 2,784. (No model.)

To all whom it may concern:

Be it known that I, ROBERT C. SCHEMML, a citizen of the United States, residing at Union City, in the county of Randolph and State of Indiana, have invented new and useful Improvements in Devices for Turning Backstays, of which the following is a specification.

My invention relates to devices for turning backstays such as used in trimming buggies, carriages, and the like; and its novelty and advantages will be fully understood from the following description and claims when taken in conjunction with the accompanying drawings, in which—

Figure 1 is a plan view of my improved device with the pressing-pieces shown as secured in their closed positions. Fig. 2 is an enlarged detail longitudinal section of the device, the same being shown with the pressing-pieces at the upper side of the body open and those at the lower side closed. Fig. 3 is an enlarged transverse section illustrating the upper and lower pressing-pieces in the same positions as in Fig. 2.

Referring by letter to the said drawings, A is the body of the device, which is preferably of wood and rectangular or oblong in form. This body is preferably provided at its opposite sides with pressing-pieces and certain appurtenances thereof, as shown, in order to enable the device to turn two backstays at the same time. I desire it distinctly understood, however, that when deemed expedient the body may be provided with pressing-pieces and the appurtenances thereof at but one side without departing from the scope of my invention.

B represents longitudinal pressing-pieces, of which there are two at each side of the body A, and C represents the end pressing-pieces, of which there is one at each side of the body. Said pressing-pieces are connected by pieces of flexible material to the body, so as to enable them to fold in upon the sides of the same, and their contiguous ends are beveled, so as to rest close together when they are folded in upon the body.

By preference the longitudinal pressing-pieces B at each longitudinal edge of the body A are flexibly connected to the edge by a piece of leather D, which is interposed between a

reinforcing-strip E of leather or other suitable material, and the said edge and is made to cover metallic strengthening-strips D', suitably connected to the inner faces of the pressing-pieces, as indicated by F, so as to prevent said strips D' from injuring the backstays operated on. The transverse pressing-pieces C are likewise connected to the end edge of the body by a piece of leather or other suitable flexible material G, which is interposed between a reinforcing-strip H of leather and the said edge and is made to cover metallic strengthening-strips H', suitably connected to the inner faces of the pieces C, as indicated by H'', so as to prevent said strips H' from injuring the backstays.

I I are plates connected to the outer sides of the end pressing-pieces C. These plates are respectively provided with outwardly-extending arms a, provided with eyes b, an arcuate slot c, and an aperture d. The apertures d of said plates are designed to receive studs e on arms or projections J, while the slots c are designed for the play of bolts f, through the medium of which the arms or projections are connected to the plates. Said arms or projections are so arranged as to extend inwardly from the pressing-pieces C when said pieces are folded in upon the body A for a purpose presently to be described.

K K are keepers, of metal or other suitable material, which are connected to the outer sides of the longitudinal pressing-pieces B and are provided with overhanging portions g, and L L are fastening-arms pivotally connected to the outer sides of the pressing-pieces B. The arm L of each pressing-piece B at each side of the body A is adapted to be swung into engagement with the keeper K of the other pressing-piece and when so placed are adapted to hold the pressing-pieces against the sides of the body A. The arms L, adjacent to the end pressing-pieces E, are also adapted when placed in engagement with their complementary keepers K to rest over the arms J of the pieces C and hold said pieces against the sides of the body, as shown in Figs. 1 and 2.

By virtue of the pivotal connection of the arms J to the plates I the said arms may be swung from beneath the arms L, and the pressing-pieces C may be released, when de-

sirable or necessary, without releasing the pressing-pieces B.

I provide springs M at the ends of the device and springs N at the sides of the same. The 5 springs M comprise coils h, which are mounted on studs i, connected to the longitudinal edges of the body A, and arms j, which extend loosely through the eyes b of the arms a on plates I. The springs N likewise comprise coils k, which are mounted on studs l, connected to the longitudinal edges of the body A, and arms m, which loosely extend through eyes n in arms p on the pressing-pieces B.

15 As best shown in Fig. 1, the lower arms of the springs M N extend loosely through the lateral arms on the upper pressing-pieces, while the upper arms of said springs extend loosely through the lateral arms of the lower 20 pressing-pieces. Consequently it will be seen that when the pressing-pieces B C are folded in against the body A the tension of the springs M N is exerted toward the horizontal plane of the body, with the result that the 25 outer portions of the pressing-pieces B C are held firmly against the upper and lower sides of the body A, and stretching of the flexible strips D G, which is liable to occur, is effectually prevented from rendering the operation 30 of the device imperfect. When the arms L of the pressing-pieces B are secured in the keepers K and the arms J of the pressing-pieces C are secured beneath the adjacent arms L, said arms L and J securely hold the 35 inner edges of the pressing-pieces against the stays interposed between them and the body. It will also be appreciated that when the pressing-pieces B C are released the springs M N, by reason of the leverage afforded by the 40 arms a p, will return said pressing-pieces to and hold them in their open position, thus permitting of the convenient placing of a backstay on the body.

In using my improved device the stays, 45 made up of a stiff filling-piece s and a leather covering t, as shown in Fig. 1, are placed upon the body A between the pressing-pieces B C, the said stay having been previously cut to form and pasted. When the stay is properly 50 placed in position, the pressing-pieces B at the one side of the body are swung over upon the stay and body and secured in such position by placing the arms L in engagement with the keepers K. The transverse or end 55 pressing-piece C is then swung inwardly

through the medium of its arm J and is secured in such position by placing said arm J under one of the arms L.

When it is desired to remove the finished stay, it is simply necessary to release the arms 60 L from the keepers K, when the springs M N will move the pressing-pieces to their open positions. The finished stay may then be readily removed and another stay put in its place.

65 I prefer to use springs M N, constructed and applied as shown and described. I do not desire, however, to be understood as confining myself to said springs, as such changes or modifications may be made in practice as fairly fall within the scope of my claims.

Having thus described my invention, what I claim is—

1. In a device for turning backstays, the combination of a body, pressing-pieces having lateral, outwardly-directed arms, provided with apertures, strips of flexible material connecting the pressing-pieces to the body, whereby said pressing-pieces are adapted to be swung toward and from the body, 75 suitable means for securing the pressing-pieces in their closed position, and springs connected to the edges of the body and having arms extending through the apertures of the arms on the pressing-pieces, substantially 80 as and for the purpose set forth.

2. In the device for turning backstays, the combination of the body having studs on its edges, the upper and lower pressing-pieces having lateral, outwardly-directed arms provided with apertures, strips of flexible material connecting the pressing-pieces to the body, whereby said pressing-pieces are adapted to be swung toward and from the body, 90 suitable means for securing the pressing-pieces in their closed position, and springs coiled about the studs on the body and having their upper arms extending through the apertures of the arms on the lower pressing-pieces, and their lower arms extending 95 through the apertures of the arms on the upper pressing-pieces, substantially as and for the purpose set forth.

In testimony whereof I have hereunto set my hand in presence of two subscribing witnesses.

ROBERT C. SCHEMME.
